C. LOMBARDO

RESERVE FUEL VALVE

Filed June 5, 1925

Attorney

UNITED STATES PATENT OFFICE.

CHARLES LOMBARDO, OF WATERFORD, NEW JERSEY.

RESERVE-FUEL VALVE.

Application filed June 5, 1925. Serial No. 35,187.

To all whom it may concern:

Be it known that I, CHARLES LOMBARDO, a citizen of the United States, residing at Waterford, in the county of Camden, State of New Jersey, have invented certain new and useful Improvements in Reserve-Fuel Valves; and I do hereby declare the following to be a full, clear, and exact description of the invention, such as will enable others skilled in the art to which it appertains to make and use the same.

This invention relates to new and useful improvements in attachments for automobile gasoline tanks, and particularly to attachments which retain a reserve supply of gasoline in the tank.

One object of the invention is to improve the construction of devices of this character wherein the operating means is conveniently located, and which mechanism is arranged to be locked against accidental displacement.

Another object is to provide an operating mechanism, which is associated with the valve in such a manner that the valve may be quickly and easily held in any of its different operative positions.

A further object is to provide an operating device of this character which is simple and easy in its construction and operation, and which can be manufactured at a comparatively low cost.

Other objects and advantages will be apparent from the following description when taken in connection with the accompanying drawing.

In the drawing:

Figure 1 is a vertical sectional detail view through a portion of a gasoline tank showing the invention mounted therein.

Figure 2 is an enlarged vertical sectional view through the invention.

Referring particularly to the accompanying drawing, 10 represents a portion of a gasoline tank, such as is ordinarily used in connection with automobiles, and having the drain or sediment chamber 11 screwed into the bottom thereof, the threaded nipple 12, on the upper end of said chamber being inferiorly threaded to receive the lower end of the vertical tube 13, which is disposed in the tank. In the lower portion of the tube 13, immediately above the nipple 12, is an opening 14, and at a suitable distance above this opening is a second opening 15, the latter of which serves as an outlet for the regular supply of gasoline to flow out of the tank,

while the former serves to permit the escape of the reserve supply held in the tank, above said opening 14, when this opening is in closed position.

Snugly fitted in the tube 13 is a second tube 16, said tube having the openings 17 and 18 in the side of its lower end arranged in such manner that when the former registers with the upper opening 15, the other is out of register with the lower opening 14, and vice versa, with the result that upon rotating the tube 16, within the tube 13, in one direction, the normal supply of gasoline will flow out through the registered openings 17 and 15, and upon rotating the tube 16 further, the openings 18 and 14 will register to permit the reserve supply of gasoline to escape. The lower end of the inner tube 16 extends a short distance below the tube 13, and disposed through this end of the tube 16 is a pin 19, which holds the tube against upward movement.

Disposed transversely through the upper portion of the inner tube 16 is a pin 20, and resting on this pin is a lead washer 21, which serves to prevent leakage of gasoline upwardly through the tubes, and also as a seat for the lower end of the coil spring 22, which is disposed in the tube. On the upper end of the spring 22 is a metal plug 23, and engaged on the upper end of the plug is the inner cam portion 24, of a lever 25, which is pivotally mounted on a transverse pin 26, disposed through the upper end of the tube 13, above the upper end of the tube 13.

A suitable packing 27 is disposed around the upper end of the tube 13, at the point where said tube extends through the upper wall of the tank, and engaged on the upper end of the tube 13 is a disk 28, which is held against relative rotation with respect to the tube. The portion of the tube 13, above the disk, is formed with a series of vertical notches 29, within any one of which the lever 25 is adapted to be seated whereby to hold the tube 16 against accidental rotation. A nut 30 is engaged on the upper end of the tube 13, and bears on the disk 28 to hold the same on the upper face of the tank. On the disk are graduations which register with the notches 29, so that the operator may seat the lever in accordance with the position of the valve and the condition or level of the gasoline in the tank.

What is claimed is:

1. The combination with a fluid tank hav-

- ing an outlet in the bottom thereof, a tube disposed in the outlet and extending through the top wall of the tank and having outlet openings in its lower portion, of a rotatable tube within the first tube and having openings for successive registration with the openings of the first tube, an operating means on the upper end of the inner tube for engagement with the adjacent end of the outer tube to hold the inner tube in different operative positions, and means within the inner tube for holding the operating means in and out of engagement with said outer tube.
- 15 2. The combination with a fluid tank and the vertical outlet tube extending through the top wall of the tank and having vertically spaced outlet openings in its lower portion, of a rotatable tube in the first tube and having openings for registration with the first openings, a lever pivotally supported in the upper end of the inner tube, the upper end of the outer tube having notches for receiving said lever, and means in the inner

tube engaged with the lever for holding the lever in and out of said notches.

3. The combination with a fluid tank and its apertured outlet tube extending into the bottom of the tank and through the upper wall thereof and having outlet openings in its lower portion, the upper end of the tube having notches, an apertured tube rotatably disposed in the first tube, a cam lever pivotally mounted in the upper end of the second tube and arranged to engage in the said notches, a dial surrounding the upper end of the first tube and having indications opposite the notches, a cam lever pivotally supported in the upper end of the second tube and arranged to enter said notches, a spring seat supported in the second tube, a member disposed beneath the cam portion of the lever, and a spring in the tube between the seat and member.

In testimony whereof, I affix my signature.

CHARLES LOMBARDO.
